UNITED STATES PATENT OFFICE.

MARY LEWIS REDD, OF COLUMBUS, GEORGIA.

DESIGN FOR A FLAG-HOLDER FOR SOLDIERS' GRAVES AND OTHER DECORATIVE PURPOSES.

46,349.

Specification for Design.

Patented Sept. 1, 1914.

Application filed May 18, 1914. Serial No. 839,462. Term of patent 7 years.

To all whom it may concern:

Be it known that I, MARY LEWIS REDD, a citizen of the United States of America, residing at Columbus, in the county of Muscogee and State of Georgia, have invented a new, original, and ornamental Design for a Flag-Holder for Soldiers' Graves and other Decorative Purposes, of which the following is a specification, reference being had to the accompanying drawing, forming part thereof.

I claim—

The ornamental design for a flag holder for soldiers' graves, and other decorative purposes as shown.

MARY LEWIS REDD.
